UNITED STATES PATENT OFFICE

EDWARD GEARON, OF CHICAGO, ILLINOIS

CIGARETTE

Application filed September 20, 1928. Serial No. 307,269.

My invention relates to cigarettes, and more particularly to means for specially preparing the same, and my main object is to prepare the cigarette with a novel mouthpiece which filters the nicotine from the smoke so as to permit the latter to be inhaled without harmful effects.

A further object of the invention is to incorporate in the novel mouthpiece a member 10 of absorbent material, which takes up and retains the nicotine juices yielded by the smoke, yet permits the latter to pass freely to the mouth.

A still further object of the invention is 15 to locate in the end of the novel mouthpiece a screen which traps fine tobacco particles and dust, so as to filter the smoke and render the same free of foreign matter before it enters the mouth.

20 Another object of the invention is to encase the novel mouthpiece in a semi-rigid gelatine jacket, which serves as a guard for any moist or liquid matter which may have a tendency to escape in a lateral direction from the mouthpiece, and confines it so that such matter may not come in contact with the lips between which the mouthpiece is held.

25 A final, but nevertheless important object of the invention is to encase the same in a fabric wrapper, which forms a neat closure and a sanitary container for the mouthpiece.

With the above objects in view and any others that may suggest themselves from the 30 specification and claims to follow, a better understanding of the invention may be gained by reference to the accompanying drawing, in which

Figure 1 is a perspective view of a typical cigarette equipped with the novel mouthpiece;

Figure 2 is an enlarged perspective view of the jacket previously referred to;

Figure 3 is a perspective view of the 40 screen;

Figure 4 is a similar view of the absorbent member;

Figure 5 is a fragmental perspective view 45 of the end of the mouthpiece, showing the appearance of the wrapper thereat; and

Figure 6 is a longitudinal section through the mouthpiece.

It is a familiar fact that smoking occasions the absorption of more or less nicotine into the mouth and the respiratory system and 55 many efforts have been made in the past to check the nicotine by the use of filters and other mechanical appliances. Most attempts in this direction have been applied, as far as I have been able to observe, to tobacco 60 pipes and cigar or cigarette holders. Since cigarettes have gained wide popularity in recent years, I have considered it advisable to improve the same to reduce the harmful effects to a minimum and make the smoking 65 thereof more pleasant.

Referring specifically to the drawing, 10 denotes the cigarette, which may be of any suitable type. For the purposes of my invention, I fit one end of the cigarette into a semi-rigid gelatine cup 11, which constitutes the mouthpiece for the cigarette. The cup 10 is sufficiently firm to exert a substantial hold upon the cigarette so as to properly support the same; however, the cup is mainly intended to serve as the jacket previously referred to, this function thereof being explained in a later section.

In the mouthpiece, the end of the cigarette first receives a cylindrical pad 12 of absorbent cotton or similar material. This pad is disposed in endwise contact with the end of the cigarette and is axially bored as indicated at 13; also, the pad is peripherally fluted as indicated at 14, in a longitudinal direction, 75 the flutes extending entirely around the pad. The latter snugly fits the cup 11, yet the flutes 14 form passages between the latter and the pad.

The pad 14 extends to within a close proximity of the bottom 11a of the cup 11, and is spaced from such bottom by the interposition of the screen 15. This member is a patch of finely meshed gauze, which fits within the bottom 11a of the cup and is cut with a scalloped rim 16 which by folding within the sides of the cup lends stability to the screen; in other words, the scalloping 16 constitutes the screen in the nature of a cup formed to fit the bottom of the cup 11. The latter is 100

perforated with a relatively large central aperture 11b and with a number of smaller intermediate apertures 11c.

In the sense that the cup 11 encloses the pad 12 and the screen 15, and also receives the end of the cigarette 10, it may be properly called a jacket, as mentioned. However, in order that the mouthpiece may be given a more finished and sanitary appearance, I prefer to impose upon the jacket a silk wrapper 17, whose free end is gathered as indicated at 18 and stitched as shown at 19 to make a neat and compact closure. The cigarette is now completed and may be packed in quantities as the custom may dictate.

In pointing out the characteristics of the features described above, the pad 12 may first be mentioned. While this pad is perforated both centrally and peripherally to permit smoke to pass through it, it is of such an absorbent nature as to permit the larger portion of the smoke to pass through the same and yield its nicotine content. As is well known, the nicotine is carried by the moisture in the smoke and if permitted to accumulate settles in the form of a liquid or juice. Thus, to keep in check the moisture within its cells, the pad occasions the deposit of the nicotine particles and as the cigarette is smoked becomes more or less impregnated with the nicotine. It may thus be safely assumed that the smoke is divested of the greater portion of its nicotine content when it has emerged from the pad. The smoke now must pass through the screen 15, and this will supplement the function of the pad to some degree, and also check what particles of fine tobacco or dust may be carried by the smoke, so that the same may not enter the mouth. Finally, the smoke will issue from the mouthpiece through the apertures 11b and 11c and the meshes of the wrapper 17, at which stage it may be considered sufficiently pure for practical purposes.

The jacket 11, while constituting a firm container and holder for its contents, is also intended as a guard to shield the lips of the smoker from any moisture of tobacco or nicotine which may escape from the pad 12 by reason of excess absorption or heat. Thus, no bad taste will be experienced while holding the mouthpiece between the lips. Also, the gelatinous material of the jacket is slowly soluble and therefore will not clog up a wash-bowl or floor drain in which the discarded cigarette may be thrown.

Ordinarily, the nicotine in a cigarette accumulates in the mouthpiece end as the process of smoking goes on until such end becomes so clogged that the smoker feels the bitter taste of the nicotine and therefore discards the cigarette while a substantial portion of tobacco is still present in the end referred to. In the case of my novel mouthpiece, this condition is avoided as the nicotine does not ac-

cumulate in the mouthpiece end of the cigarette, but is constantly drawn to lodge in the pad 12, which is of a nature to both absorb the nicotine yet permit the free passage of the smoke without carrying the bad taste of the nicotine. Thus, the entire cigarette may be smoked, adding to the period of the enjoyment thereof and rendering smoking more economical.

While the novel mouthpiece has marked utility, it may be enhanced in appearance by coloring the jacket or the wrapper; also, these parts may be flavored or scented as the fancy may dictate to add to the attraction of the article. In conclusion, it may be said that the mouthpiece is not applied or held out in an independent sense, but is intended to merge into the cigarette as an integral part thereof, so that I am really presenting to the public a new cigarette rather than a holder or mouthpiece therefor.

While I have illustrated and described my invention in the preferred form, it will be seen that the same is capable of many minor changes and refinements as well as the application to the style of a cigar, and it is my intention to claim such changes, refinements, and application as coming within the spirit and scope of the appended claims.

I claim:

1. A cigarette mouthpiece comprising a perforated cap fitted upon one end of the cigarette, an absorbent pad within the cap, a fabric screen between the pad and the crown of the cap, and a fabric wrapper imposed upon the cap.

2. A cigarette mouthpiece comprising a perforated cap fitted upon one end of the cigarette, an absorbent pad within the cap, and a fabric screen between the pad and the crown of the cap, said screen being marginally flanged to seat in the wall of the cap.

3. A cigarette mouthpiece comprising a perforated cap fitted upon one end of the cigarette, an absorbent pad within the cap, a fabric screen between the pad and the crown of the cap, and a fabric wrapper imposed upon the cap, said wrapper being gathered at its outer end and secured.

In testimony whereof I affix my signature.

EDWARD GEARON.
